UNITED STATES PATENT OFFICE.

JOHN W. KING, OF SYRACUSE, NEW YORK.

TRAIN-STOPPING DEVICE.

Application filed December 16, 1922. Serial No. 607,382.

To all whom it may concern:

Be it known that I, JOHN W. KING, a citizen of the United States of America, residing at Syracuse, Onondaga County, 5 State of New York, have invented certain new and useful Improvements in Train-Stopping Devices, of which the following is a specification.

This invention relates to improvements 10 in train stopping devices, and has for its object to provide novel, simple and effective means for positively stopping a train whenever the engineer fails to see or heed the usual stop and danger signals which are 15 located at intervals along the right of way. A particular object is to effect the stopping of trains by the application of the well-known air-brakes, wherein the setting of the brakes is accomplished by a combination 20 of agencies over which the engineer has no control. A further object is to provide automatic means for closing the throttle through a reduction of the main reservoir pressure, which is effected simultaneously with the 25 drawing-off of the train-line pressure. A further object is to provide a novel track device, which may be operatively connected with and controlled entirely by certain of the semaphores which are usually disposed 30 adjacent the railroad tracks. And a further object is to generally improve, simplify and render more positive and automatic train stopping devices of the class.

I attain these objects by the means set 35 forth in the detailed description which follows, and as illustrated by the accompanying drawings, in which—

Figure 1 is an outline side elevation of a locomotive to which my improvement is 40 applied. Fig. 2 is a top-plan view of the same. Fig. 3 is a fragmentary plan view of a railroad to which the track devices are applied. Fig. 4 is a central vertical section, taken on line 4—4 of Fig. 3; showing by 45 full and dotted lines the operated and idle positions of the knife which severs the several air lines. Fig. 5 is a front end view of the locomotive; showing the track and pilot attachments. Fig. 6 is a detached top 50 plan view of the knife support. Fig. 7 is a side view of the same. Fig. 8 is a broken outline view of a pilot; showing a modification of air line supporting means. Fig. 9 is a central vertical section taken on line 55 9 of Fig. 8. Fig. 10 is a diagrammatic view of a triple-valve, an air reservoir and

the cylinder which closes the throttle. Fig. 11 is a side view of a locomotive pilot; showing a modified application of the track and pilot attachments. And Fig. 12 is a front 60 end view of the same.

In the drawings, 2 represents generally the locomotive, 3 is the pilot, 3' the deck, and 3" the beam of the pilot. 4 represents the lever which operates the throttle-valve (not shown) which is usually disposed in the dome 2' of the engine boiler. Other parts of the locomotive which are not material to the operation of my improvement will be omitted from this description. Aside 65 from the throttle lever, the only parts usually carried by locomotives that enter into the scheme or relationship of the present invention, are the certain instrumentalities included in the air-brake system, which comprise the train-line 5, by means of which the brakes are set and released, the main reservoir 5', which is usually carried by the engine and which is charged with an air pressure of higher tension than the train-line, and the engineer's valve 5", by which he controls the brakes and other air attachments. The air pressure is usually supplied 70 by a well-known compressor, which is not shown.

The trains of practically all the railroads in this country, are operated by what is known as the semaphore system of signals, the semaphores being located permanently at suitable intervals alongside the 90 rights of way, and are usually operated by signalmen who are stationed near the semaphores. As a rule, these semaphores have different significations, as for example, the "caution" signals, and the "stop" signals. 95 The present invention is intended to operate in connection with the stop signals, and is in no wise connected with or controlled by the other semaphores. Semaphores and signal towers are so well known and understood that it is not deemed necessary to show either of these parts in the present case.

The primary object of the present invention is to effect the stopping of trains, in 105 cases where the engineer, for any reason, runs by, or attempts to run by, a semaphore that has been set for a "stop", by the opening and exhausting of the air-pressure carried by the train-line 5. This is accomplished by the cutting of the train-line, rather than by the operation of valves, coup- 110

lings and the like. Secondary objects of the invention include the closing of the throttle and the effecting of certain reductions of the main reservoir pressure simultaneously with the severing of the train-line. To accomplish these objects in part, I provide a novel track mechanism, which in the preferred arrangement (see Figs. 3 and 4) is located between the rails 6, the latter being secured to ties 6', two of which also support the body 7 of the track device, by means of similar beams or bars 7', which extend from one tie to the other and are rigidly held in place by bolts 7^a. The body 7 is preferably made of durable metal and has similar spaced lugs 7^b, which project horizontally from the opposite sides and receive the medial portions of the bars 7'. At one end the body 7 has a horizontal flange 7^c, which rests upon and is secured to the adjacent tie 6' by bolts 6^a. The opposite ends of the bars 7' comprise upwardly facing shallow channels which receive the bottom sides of the ties 6'. The single moving part of the track device consists of a knife-like lever 7^d, which is vertically movable in a groove 7^e, the said knife being pivotally supported in said groove by a shaft 7^f, which may extend laterally beyond the rail 6 and connect in a well-known manner with the mechanism which operates a nearby semaphore (not shown). The knife 7^d, in Figs. 3 and 4, is reversed as compared with Figs. 1 and 2, and the train accordingly moves in the direction indicated by the arrow in Fig. 4. The full lines in certain of the views show the knife 7^d in operative position ready to perform its work, the dotted lines in the same views showing the knife in the idle or released position. The lower end of the knife 7^d is provided with a tooth 7^x, which engages a stop-pin 7^y whenever the knife is swung upwardly, for absorbing more or less of the strain when the knife is struck by any object moving in the direction of the arrow in Fig. 4.

Referring to Figs. 1—2 and 5 the parts of my train stopping mechanism carried by the locomotive will now be described: 8 represents a shoe or part, which is preferably made of wrought metal and mounted upon the pilot 3, and whose free end preferably projects some distance beyond the nose of the pilot, as best seen in Figs. 1 and 2. The shoe 8 is provided with rearwardly extending arms 8' and 8^a, which are respectively made rigid to the central and lateral margins of the pilot by bolts 8^b. The forward end of the shoe is forked and the arms 8^c are preferably spaced sufficiently to form a clear passage of the knife 7^d when the pilot and shoe sway laterally by the usual rolling motion of the locomotive, and the tips of the arms 8^c are preferably flared, as shown in Fig. 2, for guid-

ing the knife into the crotch of the fork in case the swaying of the pilot is greater than the normal breadth of the fork. The arms 8^c of the shoe are correspondingly perforated, as at 8^d to receive similar lengths or sections of rubber or other suitable hose 9—9' and 9^a, which in the present case comprise the "dead" ends of the train pipe 5, a main reservoir pipe 5^c, and a pipe 10' which supplies a reduced pressure obtained from the main reservoir to an auxiliary reservoir 10. The several pipes and the corresponding hose sections may be conveniently connected by means of similar elbows 9^b. The hose 9, 9', 9^a have their free ends closed by plugs 9^c, which may be provided with the usual means for draining (not shown). The hose sections are disposed directly in the path of the knife 7^d, so that all may be severed by the relatively sharp cutting edge of the knife, for drawing off the air from the train-line and the main reservoir, as well as for exhausting the air from the line which supplies the auxiliary reservoir 10.

In order to lessen the strain on the knife 7^d, during the hose cutting operation, the three hose are preferably disposed in a plane that inclines rearwardly, as best seen in Fig. 1. Immediately after the hose are cut, the knife 7^d encounters a depending angular guard or deflector 8^d (see Fig. 2), which first effects a partial twisting of the free top end of the knife and then bends it downwardly so that the pilot and other low swung parts of the locomotive and cars may pass safely over the knife until the train comes to a stop. At every operation, the knives 7^d are practically destroyed, and must be replaced by the signalmen or section crew, before another train can be stopped by the device. The engineer is supposed to carry a supply of the short hose sections for refitting the shoe 8, as shown and described. It is calculated that the expense and slight amount of labor of installing the knives and hose will be negligible, as compared with the usual loss resulting from wreckage and damage suits which invariably follow when trains run by the stop signals uncontrolled.

When the knife 7^d first enters the slot or fork of the shoe 8, it encounters and cuts the hose 9^a that forms the dead-end of the pipe 10' which supplies the auxiliary reservoir 10 with the reduced pressure derived from the main reservoir and effects the closing of the throttle, simultaneously with the setting of the brakes, by the cutting of the next hose 9', which opens the train-line 5. This opening of the train-line is only intended to effect what is known as a heavy "service" application of the brakes, rather than as "emergency" application which might result in damage to the rolling-stock.

or tracks. In order to effect this lighter application of the brakes, the bore of the pipe 5 should so be restricted as to limit the exhaust of the air, in a well-known manner. The third hose section to be cut by the knife 7^a connects directly with the main reservoir 5' by means of a pipe 5^e for drawing off a certain amount of the pressure of said reservoir. The object of this latter reduction is to so lower the main reservoir pressure, that it will be impossible for the said pressure to feed through the engineer's valve 5^a into the train-line 5, and thereby prevent or prolong the stopping of the train.

It is generally understood that whenever the train-line pressure of the brake system is reduced or exhausted by the aforesaid service application, that a train may be brought to a stop within certain limits of space or distance, and that under ordinary conditions an engineer through the operation of his brake valve (5^a) can repeatedly bring his train to a stop at practically the same point. In every case when the engineer applies the brakes for effecting a service stop, he releases the air gradually and intermittently, and in doing so, his valve 5^a temporarily shuts off any feed of the main reservoir pressure through the said valve, and he also shuts off the feed from the compressor, which otherwise would immediately restore the lost pressure in the train-line. But when the engineer's valve is set in the "running position" and it becomes necessary to stop a train without his knowledge or assistance, or without the use of his valve (5^a), it is necessary to either make an application that is heavier than the usual service reduction of the train-line, or else simultaneously reduce the main reservoir pressure and also close the throttle, in order to positively and safely stop the train within safe limits of distance by automatic means. To this end I provide a mechanism for closing the throttle valve, and also means for reducing the main reservoir pressure simultaneously with the release of the air from the train-line. These secondary objects are accomplished by the following means: The throttle lever 4 is pivoted at 4', and is provided with a spring controlled latch 4^a, which engages a rack 4^b, for holding the said lever in any desired position. The throttle closing mechanism comprises a lever 11, which is pivoted at 11' to a guide 11^a, the said lever having a longitudinal slot 11^b, which is traversed by a pin 4^c carried by the latch 4^a. The rocking of the lever 11 on its pivot, as from the full to the dotted line position in Fig. 2, withdraws the latch 4^a from the teeth of the rack 4^b and allows the throttle lever 4 to be swung on its pivot, as from the full line or open position, to the dotted line or closed position shown in

Fig. 2. The rocking of the lever 11 is effected by a block or striker 12, which is mounted on the free end of a rod 12', which in turn is attached to and is operated by a piston 12^a that is reciprocatable in a cylinder 12^b, the said piston being moved in the direction for operating the lever 11, by the charging of said cylinder with air pressure that may be derived from the auxiliary reservoir 10. As the pressure required to release the lever 4 and effect the closing of the throttle valve may be of lower tension than the normal pressure of the main reservoir 5', the latter pressure is accordingly reduced, to say 30 lbs., by means of a reducing valve 13. As reducing valves of the class are well-known and understood, the valve 13 will not be shown or described in detail. This reduced pressure is carried from the valve 13 to the hose 9 by the pipe 10', and by the same pipe to a fitting 14, which in the present case, is preferably the common and well-known triple-valve, which forms a part of the air-brake equipment of every railway car. In Fig. 10 I have shown the triple-valve in vertical section. The reduced pressure from the main reservoir enters the triple at 14' and passes to a chamber 14^a, in which is disposed a piston 14^b, which the pressure forces and holds in the position shown and by means of a small bypass or duct 14^c, the said pressure escapes past the piston 14^b into a chamber 14^d, and from that chamber into the auxiliary reservoir 10, thereby equalizing the pressure in the two chambers 14^a-14^d. The chamber 14^d is tapped by a passage 14^e, to which is connected a pipe 12^c, which conducts the air to the cylinder 12^b. As long as the pressure in chambers 14^a-14^d is equal, a slide-valve 14^f closes the passage 14^e and prevents the charging of the cylinder 12^b. When, however, the pressure in chamber 14^a is reduced, as by severing the hose 9, the pressure carried by the auxiliary reservoir 10 forces the piston 14^b downwardly, opens the passage 14^e, and allows the pressure from the reservoir 10 to flow into cylinder 12^b, for effecting the closing of the throttle, as described. When the pressure from the main reservoir to the triple 14 is again restored, the piston 14^b and valve 14^f are reversed, which effects the exhausting of the air from the cylinder 12^b, through a port 14^x of the triple, in a well-known manner. After the cylinder 12^b is relieved of pressure, a spring 12^e reverses the piston and the throttle lever 4 may again be manipulated in the usual manner, for opening and closing the throttle. The cutting of the hose 9^a, which taps the main reservoir 5', is necessary in order to effect the reduction of the high tension pressure in said reservoir corresponding to the reduction in the train-line 5, and therefore prevent any tendency of the reserve pressure

from feeding through the brake valve 5^a, for hindering the positive setting of the brakes. Otherwise to reduce the main reservoir pressure by cutting the hose 9^a, without simultaneously reducing the pressure in the pipe 5^c, which supplies reduced pressure to the triple 14, would prevent the closing of the throttle until the main reservoir pressure fell below the normal pressure of the auxiliary reservoir 10.

In Figs. 8 and 9 I have shown a slight modification of the device, which consists of splitting the nose of the pilot 3^b, for providing a clear opening or path 3^c, for the passage of the knife 7^d. The points 3^d of the pilot frame are flared, like the arms 8^e, for guiding the knife into the passage 3^c. At the rear of the points 3^d, the passage 3^c, is formed by spaced arms 15' of a guard 15, whose vertical walls are correspondingly perforated to receive the several hose sections 9—9'—9^a which perform the same functions as the hose shown in Figs. 1, 2 and 5. Rearwardly of the hose, the guard 15 curves laterally, for the purpose of bending the knife 7^d immediately after it has severed the hose, as described. The location of the track device including the knife 7^d, for this modified structure, is identical to that shown in Figs. 1, 2, 3, 4 and 5.

Figs. 11 and 12 illustrate still another modification, in which the track device which supports the knife 7^d is disposed outside of the rails 6, and the hose supporting parts are shown mounted on one end of the pilot beam 3^a. A description of the latter parts follows: 16' represents a forked bracket or part, which is disposed vertically and depends from the front face of the pilot beam 3^a, to which it is secured by bolts 16'. The top end of the bracket 16 has a flange 16^a, which rests upon the top face of the beam. The bracket 16 is preferably disposed just outside of the lateral margin of the pilot 3, which positions the forked lower-end well outside of the adjacent rail 6. The spaced arms 16^b of the member 16 are perforated to receive the horizontally disposed hose 9—9'—9^a, which form the dead-ends of the air pipes 5, 5^c and 10', as in the other views. The hose carried by the bracket 16, are preferably disposed in a vertical tier, so that the knife 7^d, when raised to the operative position, as shown, will cut the three hose simultaneously, for effecting the setting of the brakes, the closing of the throttle, and for reducing the main reservoir pressure, as described. The knife 7^d and its support are intended to be the same in all respects, as hereinbefore shown and described, and the knife is intended to be operated by a similar shaft 7^f, which may also be controlled by suitable connections with a semaphore (not shown).

Owing to the fact that the knife 7^d is

shown located rather close to the rail 6, in order to prevent possible injury to other parts of the train, the knife is arranged to encounter a deflector 17, which serves to bend the free end of the knife outwardly and downwardly as shown by the dotted lines in Fig. 12 immediately following the cutting of the hose. This practically destroys the knife, as well as the three hose and they must be replaced by new ones, before another train may be stopped by the automatic action of the device.

The cutting edge of the knife 7^d is preferably not only sharpened but is also provided with saw-like teeth; in order that the knife may have, not only a cutting action, but also a saw-like action upon the hose 9, 9'—9^a.

While I have shown and described my invention as applied to the front end of a locomotive, it is obvious that the invention may also be applied to the rear end of the tender of a locomotive so as to operate when the locomotive is running backwardly. But it is not essential that the severable sections be arranged at the extreme front or rearward end of the locomotive or tender, for in some instances it may be advantageous to position the hose at any point along the side of the locomotive or tender and to sever them by means secured to the cross-ties outside the rails, as shown in Figures 11 and 12.

It is also obvious that in the embodiment of the invention shown in Figs. 11 and 12, the knife 7^d may be disposed at a greater distance outside of the rails 6 than as shown in said figures and the forked bracket or part 16' which carries the hose 9, 9', 9^a may be mounted a corresponding distance further out toward the end of the pilot beam 3^a in order that the knife 7^d may be clear of any part of the equipment passing over the rails. In such case, since the knife 7^d cannot possibly come into contact with any part of the equipment, except the hose 9, 9', 9^a, it will be unnecessary to bend the free end of the knife outwardly and downwardly and the deflector 17 may accordingly be dispensed with.

The invention has been shown and described as applied to a steam locomotive wherein the steam throttle to the cylinders is controlled by the air actuated piston 12^a working in the cylinder 12^b. Where the device is applied to an electric locomotive the piston 12^a and associated parts may be made to actuate the switch which controls the supply of electric current to the locomotive.

Having thus described my invention, what I claim is:—

1. In a train stopping device, the combination with the train pipe and main reservoir of the air brake system carried by a locomotive, a conduit leading from the main

reservoir to any convenient point, a severable hose connected to said conduit at said point, a second severable hose adjacent said point communicating with the train pipe, 5 and a track device comprising a body fixedly secured to the cross-ties and including a knife-like member movable with respect to said body and arranged to be raised in the path of both hose when the locomotive is 10 signaled to stop, for cutting said hose to release the pressure from said train pipe for setting the brakes, and for reducing the pressure in the main reservoir to prevent the latter pressure retarding the setting of 15 the brakes.

2. The combination with an air brake system of a locomotive, a source of fluid pressure, an auxiliary reservoir and a train pipe communicating therewith, fluid pressure 20 actuated throttle operating means, a conduit between said throttle operating means aid said auxiliary reservoir, a normally closed valve in said conduit, a fluid pressure actuated normally balanced valve for 25 operating said normally closed valve, a second conduit communicating with said source of fluid pressure and said balanced valve to maintain pressure on said valve, a third conduit connected to said source of fluid pressure, severable sections forming a part of 30 said second and third conduits and the part of said train pipe remote from said source of fluid pressure, said second and third conduits and train pipe being normally closed 35 beyond said severable sections, the latter being arranged for engagement by a track device, and a track device projectable into the path of said sections, for severing them.

3. The combination with an air brake system of a locomotive, a source of fluid pressure, an auxiliary reservoir and a train pipe communicating therewith, fluid pressure actuated throttle operating means, a conduit between said throttle operating means 40 and said auxiliary reservoir, a normally closed valve in said conduit, a fluid pressure actuated normally balanced valve for operating said normally closed valve, a second conduit communicating with said source of fluid pressure and said balanced valve to 45 maintain pressure on said valve, pressure reducing means in said second conduit between said balanced valve and source of fluid pressure, a third conduit connected to said 50 source of fluid pressure, severable sections forming a part of said second and third conduits and the part of said train pipe remote from said source of fluid pressure, said second and third conduits and train pipe being 55 normally closed beyond said severable sections, the latter being arranged for engagement by a track device, and a track device projectable into the path of said sections, for severing them.

4. The combination with the train-pipe of 65 a locomotive, a source of fluid pressure for said pipe, and the cross ties of a railroad track, of a shoe mounted on the pilot of the locomotive, said shoe comprising a fork which is disposed ahead of the nose of the 70 pilot, a hose forming the dead-end of the train-pipe disposed across the fork of said shoe, a knife pivotally supported by the cross ties adapted to be swung upwardly 75 into vertical position for cutting said hose for releasing the air pressure from said pipe, means for bending said knife before the pilot of the moving locomotive contacts with the knife, and means for raising and lowering said knife. 80

5. The combination with the air brake train-pipe carried by a locomotive, a source of fluid pressure, and a railroad track including the cross ties, of a hose mounted on the forward end of the train-pipe adjacent 85 the pilot, a shoe rigidly supported by the pilot, the said shoe comprising a fork whose arms are correspondingly perforated to receive and support said hose, a body rigidly supported by one or more of the cross ties, 90 a knife-like lever pivoted in said body and movable in a vertical plane, said lever adapted when idle to be disposed horizontally for allowing trains to pass over it, said knife adapted to be raised to the vertical 95 position directly in the path of said fork, for cutting said hose and releasing the air pressure from said train-pipe whenever the engineer disregards certain signals.

6. In a train stopping device, the combination with the throttle operating lever, the pilot of a locomotive, and the air brake system including the main reservoir, the train-pipe and an auxiliary reservoir connected with the main reservoir, of separate 100 pipes carrying fluid pressure from said train-pipe, said main reservoir and said auxiliary reservoir towards the pilot, hose sections connected with the forward ends of 105 said pipes, said hose sections extending at right angles to the railway tracks, a track device comprising a knife-like lever pivotally supported by the cross ties at a pre-determined point on the road where the locomotive is to stop, said knife adapted to 110 be raised up vertically in the path of said hose for cutting said hose and releasing the pressure from said pipes in case the engineer 115 disregards a stop signal.

7. In a train stopping device, the combination with the throttle operating lever and the pilot of a locomotive, and the main reservoir and an auxiliary reservoir connected with the air brake system, of a pipe carrying 120 the air pressure from the main reservoir towards the pilot, a pipe carrying a reduced pressure derived from the main reservoir to the auxiliary reservoir and also 125

to the pilot, a hose connected to and forming the dead end of said pipe, said hose supported by the pilot and extending transversely across the pilot, a track device comprising a body rigidly supported by one or more of the cross ties at a predetermined point on the road where the locomotive may be stopped, a knife pivoted to said body adapted to be raised up vertically in the path of the pilot for cutting the several hose and releasing the air pressure from said pipes for closing the throttle and stopping the locomotive.

8. In a train stopping device, the combination with the train-pipe and the main reservoir of the air brake system carried by a locomotive and the locomotive pilot, of a hose carried by the pilot and connected with a pipe leading from the main reservoir, a hose carried by the pilot and connecting with the train-pipe, a track device comprising a body supported by one or more of the cross ties of a railroad at a point corresponding to a semaphore or other fixed signal, a knife-like lever pivoted to said body and arranged to be raised up vertically in the path of said hose whenever the locomotive is signalled to stop, adapted to cut said hose for releasing the pressure from the train-pipe for setting the brakes, and for reducing the pressure in the main reservoir for preventing the latter pressure from retarding the setting the brakes.

9. The combination with a locomotive having a pilot, a throttle lever, and an air-brake train-pipe extending towards the pilot, of a shoe mounted on the pilot, a plurality of air hose supported by said shoe one of said hose forming the dead end of said train-pipe, a main reservoir containing fluid pressure, a pipe extending from said reservoir to said pilot and supporting one of said hose, an auxiliary reservoir adapted to be charged with a reduced pressure derived from the main reservoir, a pipe extending from said auxiliary reservoir to the pilot and supporting one of said hose, means operated by fluid pressure derived from said auxiliary reservoir for closing the throttle lever, a track device comprising a body rigidly secured to one or more of the cross ties, and a knife pivoted to said body adapted to be raised up vertically in the path of said hose for cutting all of said hose and releasing the air pressure from said train-pipe and said main reservoir for

effecting the operation of the throttle lever closing means.

10. In a train stopping device the combination with the throttle lever and the pilot of a locomotive, and the main reservoir, train-pipe and an auxiliary reservoir comprising parts of the air brake system thereof, of a plurality of pipes for carrying the fluid pressure of said air brake system forward towards the pilot, a hose section mounted on the forward end of each of said pipes said hose extending at right angles to the direction of travel of the locomotive, a track device comprising a body rigidly mounted on one or more of the cross ties of the road, a knife-like lever pivoted to said body adapted to be raised up vertically in the path of said hose for severing said hose and releasing the air pressure from said pipes for setting the brakes and for closing the throttle lever whenever the locomotive is driven past a predetermined point on the road.

11. In a train stopping device the combination with a locomotive having a pilot and a throttle lever, an air brake train-pipe and a main reservoir, of a shoe mounted on said pilot, a plurality of similar hose sections supported by said shoe and extending transversely of the tracks, one of said hose sections connected with and forming the dead-end of the train-pipe, the other hose respectively forming the dead ends of pipes connected with the main and auxiliary reservoirs, means connecting the main reservoir with the auxiliary reservoir for supplying the latter with a reduced pressure, a cylinder receiving said reduced fluid pressure from the auxiliary reservoir having a piston adapted to operate the throttle lever whenever said cylinder receives a charge of fluid pressure from the auxiliary reservoir, a triple valve interposed between said reservoirs for controlling the flow of the fluid pressure to said cylinder, a track device comprising a lever pivotally mounted on the cross ties of the track, means for positioning said lever in the path of said hose whereby the movement of the locomotive past a given point effects the severing of the several hose for setting the brakes and closing the throttle. In testimony whereof I have hereunto set my hand.

JOHN W. KING.
